SHEARING DEVICE FOR CABLES

Leo Radkowski, Thomas A. Daly, and Oliver Eikel, Jr.,
Sharon, Pa., assignors, by mesne assignments, to the
United States of America as represented by the Secretary
of the Navy

Application June 6, 1952, Serial No. 292,042

2 Claims. (Cl. 89—1.7)

This invention relates to self-guided missiles of the type having electrically settable controls adapted to be pre-set from a remote control station by an electric cable extending between the missile and control station, and more particularly, to novel means for electrically disconnecting the settable controls from the control station when the missile is fired.

Missiles of the type referred to are provided with certain velocity, direction, elevation and other controls which must be pre-set before the missile is fired, this being attained by suitable electrically operated instrumentalities carried by the missile and controlled at a point remote from the missile through an electric cable extending between the station and the missile. Upon firing of the missile the electrical connections must be broken, preferably as close to the missile as practicable, which requires either a complicated separable electric connection or the severing of the cable.

The principal object of the invention is to provide a novel cable severing shear device, actuated by the cable and the relative movement between a missile and its control station.

Another object is to provide a pivoted shear device with a knife edge which latter rotates relative to the cable as it progressively moves through it.

Other objects and many of the attendant advantages of this invention will be readily appreciated as the same becomes better understood by reference to the following detailed description when considered in connection with the accompanying drawings wherein:

Fig. 1 is an elevation of the subject of the invention, attached to a fragmentary portion of a missile with which it is employed;

Fig. 2 is a section and elevation taken on line 2—2, Fig. 1;

Fig. 3 is a section taken on line 3—3, Fig. 1;

Fig. 4 is an enlarged detail as viewed in the direction of arrow 4, Fig. 2;

Fig. 5 is a section taken on line 5—5, Fig. 4;

Fig. 6 is an enlarged section taken on line 6—6, Fig. 2; and

Fig. 7 is a section taken on line 7—7, Fig. 6.

Referring in detail to the drawing, a portion of a missile M is provided with a mounting plate 10, affixed thereto in any suitable manner, this plate having a flat outer surface 11, upon which rotates a plate-like shearing device 12, pivotally secured to the mounting plate by a pivot 13. If the missile is provided with a flat surface at the position where the shearing device is to be attached thereto mounting plate 10 may be dispensed with and the shearing device may be pivotally secured directly to such flat surface. It will be understood, accordingly, that mounting plate 10 is merely an optional adapter plate which may be constructed to fit any surface on the missile casing and that the important feature is that a flat mounting surface be provided in any suitable manner.

An electric cable C, having a plurality of insulated wires therein (not shown) extends through an aperture 14, these wires, at end 15 of the cable, being connected to the various control instrumentalities (not shown) within the missile and connected at the other end 16 to the remote control station (not shown).

2

The shearing device 12 is provided with a convex cutting edge 17 which is generally involute shaped between points 18 and 20 and straight between points 20 and 21. It will be observed that the radii R between pivotal axis 22 and edge 17 or 20 increase in a clockwise direction (Fig. 1).

The shearing device is provided with an integral lever 19 having a bifurcated free end formed by legs 23, 24. As best shown in Figs. 6 and 7, a hook shaped end 25 on one end of a spring 26 extends through an aperture 27 in leg 23 and secures the spring to the latter. As best shown in Figs. 4 and 5, the other end 28 of the spring is provided with a loop 29 which seats in a slot 30 in leg 24. A lateral slot 31 joins slot 30 and permits end 28 to pass therethrough when loop 29 is to be seated in slot 30. A small shear pin 32 prevents unauthorized pivotal movement of the shearing device.

In operation, cable C is looped through the legs of the bifurcated lever and spring 26 extended with a suitable tool to dispose loop 29 in slot 30 and thus form a closure between the legs to prevent the cable from moving outwardly from the legs. End 16 is fixed to the control station and as the missile moves in the direction of axis 32 the cable tightens about the lever and rotates same in counterclockwise direction (Fig. 1), first shearing pin 32, the cutting edge then passing across aperture 14 and severing the cable.

The term "missile" as hereinafter employed in the claims is to be construed in its broadest and generic sense and to include any self-guided device such as a torpedo, rocket or the like.

Obviously many modifications and variations of the present invention are possible in the light of the above teachings. It is therefore to be understood that within the scope of the appended claims the invention may be practiced otherwise than as specifically described.

What we claim is:

1. In a torpedo of the type having electrically actuated controls and a cable having a plurality of electrical conductors therein extending between the torpedo and a control station through which the controls may be preset, the improvements in combination comprising; a cable shearing device movably carried by the torpedo for shearing the cable, and means including the cable for moving said cable shearing device in response to relative movement between the torpedo and the control station, said means including a lever carried by the cable shearing device having a bifurcated free end through which an intermediate portion of the cable detachably extends, and means for preventing unauthorized movement of the intermediate portion of the cable outwardly from the bifurcated free end.

2. A cable shearing device for use with a torpedo of the type having electrically actuated controls which may be pre-set through a cable having a plurality of electrical conductors therein extending between the torpedo and a control station, comprising; a cable shearing device pivotally carried by the torpedo for shearing the cable, and a lever carried by the cable shearing device engaging an intermediate portion of the cable for rotating the cable shearing device in response to relative movement between the torpedo and the control station, said intermediate portion being rotatable with the lever as the shearing device shears the cable.
